Primary Examiner — Karen E Eldridge Powers*Assistant Examiner* — Jasmine Mlinarcik(74) Attorney, Agent, or Firm — Norman E. Lehrer(57) CLAIM

The ornamental design for a combined hood and scarf, as shown and described.

DESCRIPTION

FIG. 1 is a front left side perspective view of a combined hood and scarf showing my new design;

FIG. 2 is a front left side perspective view thereof, as it may appear when worn and with the scarf portion shown in an open position;

FIG. 3 is a front left side perspective view thereof, as it may appear when worn with the scarf only being partially wrapped;

FIG. 4 is a front left side perspective view thereof, as it may appear when worn with the scarf completely wrapped;

FIG. 5 is a right side plan view of the combined hood and scarf; and,

FIG. 6 is a left side plan view thereof.

The partial human figure is environmental structure included to assist in showing how the claimed design may appear when worn, but does not form part of the claimed design.
